IRWIN G. BURTON, OF ASBURY PARK, NEW JERSEY.

HANDLE-FASTENING.

1,112,258.

Specification of Letters Patent. Patented Sept. 29, 1914.

Application filed January 27, 1914. Serial No. 814,681.

To all whom it may concern:

Be it known that I, IRWIN G. BURTON, a citizen of the United States, and a resident of Asbury Park, in the county of Monmouth and State of New Jersey, have invented a new and Improved Handle-Fastening, of which the following is a full, clear, and exact description.

The object of the invention is to provide 10 a new and improved handle fastening more especially designed for fastening wooden handles in hammers, axes, hatchets and other tools and devices, and arranged to permanently fasten the handle in place in 15 the socket of the tool without unduly weakening the handle.

In order to accomplish the desired result use is made of a hollow wedge adapted to be driven into a split in the end of the handle, the split terminating in a recess or a chamber, and a retaining means in the form 20 of molten metal poured into the hollow wedge to fill the said chamber and the said wedge with a view to hold the wedge against 25 outward movement.

A practical embodiment of the invention is represented in the accompanying drawings forming a part of this specification, in which similar characters of reference indicate corresponding parts in all the views.

Figure 1 is a sectional side elevation of the handle fastening as applied for fastening a handle in a hatchet; Fig. 2 is a perspective view of the hollow wedge; and Fig. 3 is a similar view of the handle.

The end A' of the wooden handle A is adapted to engage the socket B' in the tool B of any approved construction. The handle end A' is provided with a lengthwise- 40 extending split A² terminating in an opening or recess A³ and into the said split A² is adapted to be driven a hollow wedge C so as to spread the handle end A' in the socket B' to securely fasten the end A' in 45 the socket B', as will be readily understood by reference to Fig. 1. The wedge is hollow throughout its extent and is in the form of a shell approximately rectangular in shape and open at both ends.

50 In order to prevent the wedge C from becoming loose, use is made of molten metal D poured into the hollow wedge C so as to fill the opening or chamber A³ as well as the hollow wedge C, it being understood that 55 as soon as the molten metal hardens it se-

curely locks the hollow wedge C against outward movement in the split A². It is understood that the opening A³ is considerably larger than the opening at the inner or small end of the wedge C and hence when 60 the metal D has set and hardened in the opening A³ and in the wedge it forms a very strong bar against the wedge pulling out of the split when the tool is used.

From the foregoing it will be seen that 65 the hollow wedge serves to spread the handle end A' in the socket B', and at the same time the metal in filling the hollow wedge and being held in the opening A³ prevents the wedge from outward movement and 70 consequently the handle end A' is permanently and very securely fastened in the socket B' of the tool B.

Having thus described my invention, I claim as new and desire to secure by Letters 75 Patent:

1. In combination with a handle having a split and an opening into which leads the inner end of the said split, a wedge in the form of a hollow shell open at both ends, 80 the said wedge engaging the said split, the inner open end of said wedge being of less size than the said opening in the handle and reaching to the same and a material capable to set and harden and filling the said opening and the said wedge.

2. In combination a tool having a socket, a handle having a socket end fitting into the said socket, the said socket end being provided with a transverse opening and a split 90 leading from the terminal of the handle end to the said opening, a wedge in the form of an approximately rectangular shell, hollow throughout its extent and open at both ends, the said wedge being driven into the 95 said split to spread the socket end of the handle in the said socket, the said transverse opening in the socket end of the handle being larger than the opening at the inner or small end of the said wedge and a metal 100 filling the said transverse opening and the said hollow wedge.

In testimony whereof I have signed my name to this specification in the presence of two subscribing witnesses.

IRWIN G. BURTON.
